UNITED STATES PATENT OFFICE.

PAUL MOHRMANN, OF CHICAGO, ILLINOIS, ASSIGNOR TO FRIEDELEY-VOSHARDT CO., OF CHICAGO, ILLINOIS, A CORPORATION OF ILLINOIS.

DESIGN FOR A BACK PLATE FOR LIGHTING-FIXTURES.

47,540.

Specification for Design.

Patented July 6, 1915.

Application filed March 20, 1915. Serial No. 15,963. Term of patent 3½ years.

To all whom it may concern:

Be it known that I, PAUL MOHRMANN, a citizen of the United States, residing at Chicago, county of Cook, and State of Illinois, have invented a new, original, and ornamental Design for a Back Plate for Lighting-Fixtures, of which the following is a specification, reference being had to the accompanying drawing, forming a part thereof.

Figure 1 is a side elevation of a back plate for lighting fixtures, showing my new design. Fig. 2 is a plan view of the same.

I claim—

The ornamental design for a back plate for lighting fixtures, as shown.

PAUL MOHRMANN.
